UNITED STATES PATENT OFFICE.

ARTHUR DANBY, OF PHILADELPHIA, PENNSYLVANIA, ASSIGNOR TO
EDWARD F. MASON AND GEORGE N. SCHOFIELD.

DESIGN FOR CARPET FABRIC.

SPECIFICATION forming part of Design No. 23,990, dated February 5, 1895.

Application filed February 15, 1894. Serial No. 500,309. Term of patent 3½ years.

To all whom it may concern:

Be it known that I, ARTHUR DANBY, a subject of the Queen of Great Britain, residing in the city of Philadelphia, State of Pennsylvania, have invented and produced a certain new and original Design for a Rug, of which the following is a full, clear, and exact description, reference being had to the accompanying drawing, forming a part of this specification.

My invention relates to the surface ornamentation of Wilton and other carpet fabrics, and consists of the design therefor shown in the accompanying drawing in which is represented the design upon a carpet fabric.

The center panel A, which is the main feature of the design, (and which forms the subject matter of a separate application for patent) consists of leaf-like figures *a* joined to each other at the base or end, and forming

together a nearly round panel, inclosing as a center figure a bouquet *b* of leaves and buds. The side pieces B B each consist of the dependent bunches *d* of leaves and fruit, as the principal figure, with a pair of leaf-like figures *c* as a filling.

Having thus described my invention, I claim—

The design for carpet fabric, consisting of the floral panel A and the side pieces B B; substantially as shown and described.

In testimony whereof I have hereunto affixed my signature this 6th day of February, A. D. 1894.

ARTHUR DANBY.
